United States Patent Office

Des. 218,191
Patented July 28, 1970

218,191

COFFEE MAKER OR THE LIKE

Malen Z. Tevolitz, Monroe, Conn., assignor to Sperry Rand Corporation, New York, N.Y., a corporation of Delaware

Filed Nov. 25, 1968, Ser. No. 14,615

Term of patent 14 years

Int. Cl. D7—04

U.S. Cl. D44—26

FIG. 1

FIG. 2

FIG. 4

FIG. 3

FIG. 5

FIG. 6

FIG. 1 is a perspective view of a coffee maker or the like showing my new design with the serving member omitted;

FIG. 2 is a side elevational view with the serving member in place;

FIG. 3 is a left end elevational view;

FIG. 4 is a top plan view;

FIG. 5 is a bottom plan view; and

FIG. 6 is a perspective view of the serving member.

I claim:

The ornamental design for a coffee maker or the like, as shown.
